METHOD AND MEANS FOR FORMING A COCKLE FINISH IN PAPER

Henry P. Dixson, John C. Nelson, Arnold G. Beaman, and Marvin H. Buhner, Appleton, Wis., assignors to Fox River Paper Corporation, Appleton, Wis., a corporation of Wisconsin

Filed Aug. 3, 1962, Ser. No. 214,753

11 Claims. (Cl. 162—112)

This invention relates to a method and apparatus for forming a cockle finish in paper.

One purpose of the invention is a method of the type described resulting in a minimum waste of paper.

Another purpose is a method of forming a cockle finish in paper which does not weaken the paper.

Another purpose is a method of the type described which forms a cockle finish which has an un-artificial appearance.

Another purpose is an apparatus suitable for performing a method of cockling paper.

Another purpose is a method of cockling paper which makes maximum use of the paper web and which prevents curling of the paper.

Another purpose is a method of the type described in which the paper retains its cockle finish during subsequent storage and use.

Other purposes will appear in the ensuing specification, drawings and claims.

The invention is illustrated diagrammatically in the following drawings wherein:

FIGURE 1 is a side elevation of an apparatus for performing the method described, and

FIGURE 2 is an enlarged section through a portion of a cockling roller and the adjacent air housing.

In the past, two principal methods have been used to form a cockle finish in paper. In one system the paper web, containing a suitable amount of moisture, was allowed to dry under reduced tension. A typical method is to use a conventional air dryer, the physical construction and web tension control of which is well known to those acquainted with the art. As it dried, the paper would assume a cockle shape or configuration. The principal disadvantage of this method was that the cockling was frequently irregular and so random, that often a substantial part of the paper could not be used. There was considerable waste. In addition, there was a tendency for the cockling to flatten out when the paper was later cut and stored.

The second prior method of cockling paper was to do it by embossing paper already dried. The flat dried web was carried into the nip of a male and female pair of rolls whose surfaces have an engraved design. This design gave raised and depressed areas in the paper by virtue of the pressure in the nip. The rotation of this pair of rolls made for a continuous process. In such an operation the fibers of the paper are actually rearranged which has a very weakening effect on the paper. In addition, the paper did not have a truly un-artificial appearance in that the irregularity of the embossing of the roll was substantially reproduced in the paper.

The present invention is designed to overcome the weaknesses of both prior cockling methods. The cockled paper of the present invention has an excellent un-artificial appearance. There is very little waste and the paper is not at all weakened during the cockling process.

Considering the apparatus illustrated in FIGURE 1, a roll of paper 10 may be used to supply a continuous paper web 12 which is directed through the cockling process described. The web 12 first moves to a sizing machine indicated generally at 14. It is customary and conventional in paper making to add size to the paper to give the paper

2

a certain smoothness and better writing properties. The size may be a surface size which is a water dispersion of conventional surface sizing agents such as starch, glue, water dispersible synthetic resins or mixtures of the same.

5 In addition to adding size a suitable amount of moisture is added and the sizing machine 14 may include a size tray 15, and rollers 16 and 18 mounted in a suitable framework 20. The paper web 12 passes through the tray 15, around the bottom roller 16, then between the two rollers and then around the top roller 18, as illustrated in FIGURE 1. After the paper web 12 is passed through the sizing machine it has a moisture content of on the order of about 30 to 33 percent. This moisture content is not a limitation, but has been found to be a satisfactory range. 10 Although the machine 14 has been described as a sizing machine, this is not necessary and it may be used just to add a suitable amount of moisture to the paper web. The bottom roller 16 may be driven through a suitable speed reducer 22, and a drive shaft 24. The drive for the shaft 24 will be described hereinafter.

From the sizing machine 14 the web 12 passes around an idler or roller 26 mounted on a framework indicated generally at 28. Near the top of the framework 28 is a cockle pattern roll 30 driven through a speed reducer 32, a coupling 34 and a suitable gear box or the like 36. The gear box may have a shaft 38 on which is mounted a sheave 40. The sheave 40 is driven by a belt 42 in a manner which will be described hereinafter.

20 Positioned directly above the cockle pattern roll 30 is an air housing 44. The lower edge of the housing, as at 46, has substantially the same curvature as roller 30, and is closely adjacent the roller. High velocity, high temperature air is directed into the housing 44 through a duct 48. The high velocity, high temperature air is then directed at the moving web of paper to press it against the cockle pattern roll 30. The exact details of the air system and in particular the housing 44 have not been shown, as this equipment is conventional.

25 Mounted in the framework 28 and positioned below and slightly to the right, as illustrated in FIGURE 1, of the roller 30, is a second cockle pattern roll 50. The roller 30 is effective on one side of the paper and the roller 50 is effective on the opposite side. The roller 50 is driven through a suitable speed reducer 52, a coupling 54 and a gear box or the like 56. The gear box has a shaft 58 upon which is mounted a sheave 60. The sheave in turn is driven by a belt 61. Positioned directly below the cockle pattern roll 50 is an air housing 62 which has an inlet duct 64. The air system for the roller 50 is 30 substantially identical to the air system for the roller 30.

35 After the paper web 12 leaves the second cockle pattern roll 50 it is directed over a suitable idler or roller 66 and then becomes part of a roll 68 mounted on a frame 70. The roll 68 may be rotated by a suitable motor or the like 72 through a belt 74.

40 The air system is preferably of the re-circulating type with fresh air brought in as needed. The main inlet duct is indicated at 76 and it feeds inlet ducts 48 and 64 which direct the high velocity, high temperature air to the air housings 44 and 62. Outlet ducts 78 and 80 connect the housings 44 and 62, respectively, to the main outlet duct 82.

45 The velocity and temperature of the air are important as the paper should be firmly pressed against the cockle pattern rolls while the hot air dries it. It is preferred that the air have a nozzle velocity of between 1,000 to 20,000 feet per minute and be at a temperature of between 300 and 700 degrees F. Although these are the preferred ranges, the invention should not be so limited.

50 It is also advantageous to heat the cockle pattern rolls. In this way the moist paper web will receive heat from

both sides and will not curl. A temperature in the range of 200 to 230 degrees F. has been found to be satisfactory, but can be higher, for example 260 degrees F.

The drive system for the cockle pattern rolls and the sizing machine may be conventional and may include a suitable motor 84 which may be positioned on the foundation 86. The motor 84 has a shaft 88 which drives a suitable belt or the like 90. The belt drives sheave 92 which in turn drives a shaft 94 extending completely across the frame. Moving from right to left, there is a sheave 96 on the shaft 94 which drives roller 50 through belt 62. A second sheave 98 on the shaft 94 drives roller 30 through belt 42. The far left end of the shaft 94 may be supported in suitable bearings 100 and may have a sheave 102 at its extreme left end. The sheave 102 drives a belt 104 which in turn drives sheave 106. Sheave 106 drives shaft 24 for the sizing machine.

A section through a typical surface for the cockle pattern roll is indicated in FIGURE 2. The surface may have random raised areas 110 and depressions 112 which resemble the surface of cockled paper. The web of paper 12 is being pressed against the surface by a stream of hot air represented by arrows 114.

The use, operation and function of the invention are as follows:

Both of the prior methods of forming a cockle finish paper had undesirable results. In the mechanical method in which dry paper was embossed by pressing it against a roller, the paper had an uneven or artificial appearance and, in addition, because the fibers were actually rearranged by the embossing, the paper was substantially weakened. The other method used for cockling paper was to permit it to dry under reduced tension so that it would cockle as it dried. The cockles in this type of formation were so irregular and so random that substantial amounts of the paper were not usable. In addition, there was a tendency for the cockles to flatten out in storage. In the present invention the paper is not weakened in any way and the cockles formed in the paper will remain. It has sufficient irregularity to give a good un-artificial appearance.

To trace a web of paper through the apparatus shown, a roll of paper 10 is used to form a web 12 which first passes through a sizing station 14. Size or starch as well as moisture are added to the paper. It is not necessary to add size and only moisture may be added. However, size is advantageous for forming good quality writing paper. In any event, at the sizing station the moisture content of the paper is brought to about 30 to 33 percent. This is the preferred range although the invention should not be so limited.

The moist paper is then directed through a first cockle pattern roll 30. The surface of the roller 30, as illustrated in FIGURE 2, has been patterned to resemble cockled paper. There are random or irregular bumps and depressions which give unpredictable regularity or a uniform irregularity. High velocity, high temperature air, for example on the order of about 1,000 to 20,000 feet per minute and at a temperature of between 300 and 700 degrees F. is directed at the paper to press it against the cockle pattern roll. The paper is dried as it is pressed against the roller. Preferably the roller is also heated so that there will be no curling of the paper. It is important that the air have a high velocity so that the paper will be firmly pressed against the roller. The temperature is also very important so that the paper will rapidly dry. The air pushes the moist, plastic web of paper into the depressions on the cockle pattern roll. The paper is therefore guided as it dries so that it forms a suitable cockle finish. The paper does not necessarily form the same texture as the embossing roller. And in fact, as the paper dries, it may move slightly, for example as much as a quarter of an inch, on the cockle pattern roll. The important point is that the cockle pattern rolls guide the paper in the formation of cockles.

After the paper leaves the first cockle pattern roll it is taken to a second cockle pattern roll which treats the opposite side. This is necessary to prevent curling. In addition, the pattern on the second roller will normally not be the same as that on the first roller so that the second side is treated in a different manner which further adds to the random regularity or uniform irregularity. The air in the second housing which directs air against the second roller is generally at the same temperature and pressure as that applied at the first roller. From the second roller the paper is taken to a suitable roll where it is wound up for later cutting and storage. The invention should not be limited to only two pattern rolls as there may be two, four, six, etc., units depending upon the web speed desired through the system. There must be a sufficient number of units to dry the paper to about five percent moisture content.

An important point is the paper does not necessarily make a true copy of the pattern on the rolls. The rolls guide the paper and allow it to form a proper cockle. The paper is dried as it is pressed against the cockle pattern roll. Paper formed in this manner will hold its cockling during storage, and of great importance is the fact that there is very little waste paper.

The web of paper moving through the system will be under some tension, but not nearly the degree of tension used to form smooth paper. The web will be moving at reduced tension to permit the paper to cockle. However, the tension will not be as low as that used in the conventional air drying process described above.

Whereas the preferred form of the invention has been shown and described herein, it should be realized that there are many modifications, substitutions and alterations thereto within the scope of the following claims.

We claim:

1. A method of forming a patterned finish in paper including the steps of bringing a continuous web of paper to a suitable moisture content for providing said patterned finish without rearranging the fibers in the paper, directing high velocity, high temperature air against one side of the web as it moves with a moving patterned surface so that the web is pressed against the surface as it dries, thereafter directing high velocity, high temperature air at the opposite side of the web as it moves with a second moving patterned surface so that the opposite side of the web is pressed against the surface as it dries.

2. The method of claim 1 further characterized in that the moisture content of the web as it moves into the high velocity, high temperature air, is on the order of about 30 to 33 percent.

3. The method of claim 1 further characterized in that the high velocity, high temperature air has a velocity on the order of about 1,000 to 20,000 feet per minute.

4. The method of claim 1 further characterized in that the temperature of the high velocity, high temperature air is on the order of about 300 to 700 degrees F.

5. The method of claim 1 further characterized in that said web moves under a tension lower than that used in forming a smooth finished paper.

6. The method of claim 1 further characterized by and including the step of heating said moving patterned surfaces.

7. The method of claim 6 further characterized in that said cylindrical surfaces are heated to a temperature on the order of about 200 to 230 degrees F.

8. The method of claim further characterized in that said web is brought to a moisture content on the order of about 30 to 33 percent by adding size to the web.

9. Apparatus for forming cockle finish paper from a continuous web of paper including means for adding moisture to the paper web, a first cockle patterned roller and means for rotating said first roller, means opposite said roller for directing high temperature, high velocity air at the web of paper moving with said first roller, a second cockle patterned roller, spaced from said first

roller, and means for rotating said second roller, means for directing high temperature, high velocity air at the web of paper moving with said second roller, said first roller presenting one side of the web to the high temperature, high velocity air and said second roller presenting the opposite side of the web to the high temperature, high velocity air.

10. The structure of claim 9 further characterized in that the means for adding moisture to the web also adds size to the web.

11. The structure of claim 9 further characterized in that means for directing high velocity, high temperature

air at the web of paper moving with each of said rollers includes a housing adjacent each roller, each of said housings extending partially around its roller.
